Attorney

UNITED STATES PATENT OFFICE.

PAUL E. HERR, OF WATSEKA, ILLINOIS.

STARTING-CRANK HOLDER.

Application filed January 22, 1925. Serial No. 4,046.

To all whom it may concern:

Be it known that I, PAUL E. HERR, citizen of the United States, residing at Watseka, in the county of Iroquois and State of Illinois, have invented certain new and useful Improvements in a Starting-Crank Holder, of which the following is a specification.

This invention relates to a highly novel means adapted to be attached to the lower portion of radiator of a motor vehicle, preferably a Fordson tractor for holding the starting crank in an upright inoperative position.

One of the important objects of the present invention is to provide a device of the above mentioned character, which will prevent weeds, corn stalks and the like over which the tractor travels, from forcing the starting crank inwardly and causing the starting pin to be sheared off by cutting crank ratchet.

A further object is to provide a starting crank of the above mentioned character, wherein the same may be readily disengaged from the crank in order to permit the same to be used in starting the engine of the tractor.

A further object is to provide a starting crank holder of the above mentioned character, which is simple in construction, inexpensive, and furthermore adapted for the purposes for which the same is designated.

Other objects and advantages of this invention will become apparent during the course of the following description.

In the accompanying drawing forming part of this specification and in which like numerals designate like parts throughout the same:

Figure 1 is a side elevation of the device embodying my invention showing the same in use.

Fig. 2 is a vertical sectional view through the crank holder.

Fig. 3 is a top plan view, and

Fig. 4 is a front elevation.

In the drawing wherein for the purpose of illustration is shown the preferred embodiment of my invention, the numeral 1 designates generally my improved starting crank holder. The same comprises a bracket 2 which is formed of a single blank of sheet metal, the side edges converging gradually toward the upper end and terminating in the parallel spaced rearwardly disposed ears

3. The purpose thereof will be hereinafter more fully described.

The lower portion of the bracket 2 is bent transversely as illustrated at 4 to provide a pivotally extending flange or base 5. This flange or base 5 is provided with suitable openings 6 for receiving the fastening bolts 7 whereby the bracket may be supported at the bottom of the radiator A of a Fordson tractor at a point directly behind the starting crank B. The bracket 2 extends upwardly in spaced relation with respect to the radiator as clearly illustrated in Fig. 1.

A pin 8 extends transversely through suitable registering openings provided therefor in the ears 3 provided on the upper end of the bracket 2 and this pin provides a means for pivotally supporting the yoke member 9. This yoke is also formed of sheet metal and the inner end thereof is provided with the downwardly disposed ears 10 which cooperate with the ears 3 and through which the transverse pin 8 also extends. The forward or outer end of the yoke member 9 is cut away as illustrated at 11.

When the starting crank B is not in use, the yoke member 9 is disposed in the position shown in the drawings whereby the same will rest on the upper edge of the bracket 2 and the upper portion of the starting crank B will be disposed within a cut out portion or slot 11 provided in the forward end of the yoke member. This will hold the starting crank in an upright position whereby the ratchet associated with the starting crank is held out of engagement with the starting pin. When the tractor travels over weeds, corn stalks or the like, the same will not in any way interfere with the starting crank and result in any injury being sustained by the starting mechanism of the tractor such as frequently happens when the starting crank normally hangs below the radiator and frame of the tractor.

When it becomes necessary to operate the starting crank in starting the engine, it is only necessary to swing the yoke member 9 upwardly on its pivot 8 whereby the cut out portion 11 will be disengaged from the starting crank and the latter will thereby be free to be rotated in the usual manner.

It will thus be seen from the foregoing description, that a simple and efficient device has been provided for attachment on a Fordson tractor or the like for supporting the starting crank in an upright inoperative

position, the attachment in no way interfering with the ordinary use of the starting crank for necessitating any material alterations to the portions of the tractor to which 5 the same is attached.

While I have shown the preferred embodiment of my invention, it is to be understood that various changes in the size, shape and arrangement of parts may be resorted 10 to without departing from the spirit of the invention and the scope of the appended 15 claims.

Having thus described my invention, what I claim as new is:—

15 1. A device of the class described comprising a bracket, the same being secured at its lower end on the front of a radiator of a motor vehicle directly behind the usual starting crank, a pair of rearwardly extending ears provided on the upper end of said bracket, a yoke member, downwardly extending ears formed on the inner end thereof cooperating with the aforementioned ears, a pin extending through said ears for 20 pivotally supporting the yoke member at its inner end on the upper end of the bracket, said yoke member adapted to rest on the upper edge of the bracket when disposed in an operative position, the forward end of the 25 yoke member being provided with a cut out 30

portion for receiving the upper portion of the starting crank for holding the latter in an upright inoperative position

2. A device of the class described comprising a bracket formed of a single sheet of metal, the sides thereof converging gradually toward the upper edge of the bracket, the lower portion of said bracket being bent transversely to provide a flange, said flange adapted to be secured on the bottom of the 35 front portion of a radiator directly behind the usual starting crank of a motor vehicle, a pair of rearwardly extending ears formed on the upper portion of the bracket, a yoke member, a pair of ears formed on the inner 40 end thereof cooperating with the aforementioned ears, a pin extending transversely through said ears providing a means for pivotally supporting said yoke member at its inner end on the upper end of the bracket, 45 said yoke member adapted to rest on the upper edge of the bracket when disposed in an operative position, the forward end of the yoke member being provided with a cut out portion for supporting the upper portion 50 of the starting crank in an upright and inoperative position.

In testimony whereof I affix my signature.

PAUL E. HERR.
